TAMPERPROOF CONTAINER DEVICE

Lyndon G. Stonebraker, New York, N. Y., assignor to Liquilock, Inc., New York, N. Y., a corporation of Delaware

Application December 30, 1940, Serial No. 372,388

7 Claims. (Cl. 215—21)

This invention relates to the prevention of tampering with containers for liquids, and more particularly to devices for preventing unauthorized refilling of such containers.

An object of my invention is to provide improved securing means for tamperproof container attachments to prevent unauthorized removal of such attachments, and which is particularly applicable to the type of attachment described in my prior Patent No. 2,122,595 granted July 5, 1938.

It is also an object of my invention to provide a non-refillable container device which will lock the container against pouring of its contents upon any attempt to refill it, yet which is proof against accidental locking. In this and other respects, the invention relates to improvements in the device shown in said prior patent.

A further object is to provide, in a device of the character described, means which locks the tamperproof device against accidental operation and which also provides an auxiliary seal preventing unauthorized disabling of the tamper-proof device.

Another object is to provide securing means for tamperproof container attachments or the like which provide means for indicating unauthorized attempts at removal.

Other objects and advantages will appear as the description proceeds.

In the accompanying drawings:

Fig. 1 is a vertical sectional view of a preferred embodiment of the invention, said embodiment being shown in the neck of a bottle. In this view the parts are shown in the position which they occupy normally when the closure is in place preventing accidental operation of the tamper-proof locking means.

Fig. 2 is a view similarly to Fig. 1 but with the closure removed and with the parts shown in locking position in response to an endeavor to insert liquid into the bottle.

Fig. 3 is a view similar to Fig. 1 but with the closure removed and with the means for preventing accidental actuation of the locking means shown in a position which likewise prevents insertion of a siphon or filling tube when the means for locking the container against pouring of its contents is disabled by the means for preventing accidental actuation thereof.

Figs. 4, 5 and 6 are horizontal sectional views taken on the lines 4—4, 5—5, 6—6 respectively of Fig. 1.

Fig. 7 is an enlarged detail sectional view taken as indicated at 7—7 in Fig. 5.

Referring to the drawings, my invention is shown as applied to the neck of the bottle A although its use is not restricted to any particular type of container. The embodiment of the invention here illustrated is shown as comprising a sleeve 12, a retainer and pouring element 13, a closure 14 and a non-refill mechanism disposed within the sleeve 12. The sleeve 12 preferably has an integral flange 15 at its upper end for engagement with the neck end of the bottle A and a flange 16 at its lower end, the edge of the flange 16 forming an opening 17 for passage of the contents of the bottle and to serve as a seat for the valve or non-refill mechanism.

The non-refilling mechanism shown is of the general type disclosed in my prior Patent No. 2,122,595 granted July 5, 1938. It comprises a spool or cradle 18 mounted within the sleeve 12 for limited sliding movement, and a pair of hollow balls 19, 20, together with other cooperating elements to be described. The cradle 18 comprises an intermediate hub or body element 21 having fixed arms 22 extending longitudinally in the sleeve 12 and engaging the inner periphery thereof. Projecting from opposite faces of the hub 21 are studs or pins 23, 24 (which may be constituted by opposite end portions of a single member mounted in said hub). Each of the projections 23, 24 is adapted to enter a corresponding opening 25, 26 in the wall of a respective one of the pair of hollow balls 19, 20. In the normal position of the parts as shown in Fig. 1, the balls rest against opposite faces of the hub 21 and lie between adjacent cradle arms 22 with the ball 20 seating in and closing the opening 17 in the lower wall formed by the flange 16. With this construction, if an attempt should be made to introduce liquid into the bottle, such liquid cannot pass through the opening 17 which remains closed by the ball 20. Instead, the liquid rises in the chamber or well formed by the sleeve 12 and its lower closed end, carrying the ball 19 upward with the rise in liquid level away from the projection 23 and freeing it therefrom. The ball 19 is unbalanced as by the concentration of the weight at any suitable point, such as indicated at 27, whereby, as soon as the liquid floats said ball beyond the end of the projection 23, the ball is turned into the position shown in Fig. 2, carrying its opening 26 away from the projection. The ball is now positioned between the projection 23 and a baffle 28 mounted in the well or sleeve 12 in any suitable manner as by means of arms 29 which, in the embodiment illustrated, are integral with the baffle and engage a shoulder 30 (Fig. 7)

formed by a counter-bore in the upper end of the sleeve 12. The baffle is further secured in place by the retainer element 13 which has an overlapping engagement with the arms 29 as at 31. If desired, the baffle 28 may be provided with a cup-like extension 32 providing means for centralizing the ball 19 and increasing the difficulty of any attempt to manipulate the ball by a tool inserted from the outside. The cup 32 of the baffle 28 is so spaced from the end of projection 23 when the cradle 18 is in the position shown in the drawings that, upon the freeing of the ball 19 as aforesaid, the ball engages the cup or under part of the baffle. As the ball then turns by virtue of its unbalanced condition, a solid portion of its wall engages the projection 23 so that the cradle and the ball 29 are locked in their lowermost position, and the opening 17 of the container permanently closed. Not only is the liquid poured into the bottle neck thereby prevented from entering into the body of the bottle, but the latter is effectively and permanently locked against pouring of its contents or further use. In this connection, it is to be noted that the ball 19 is continually biased into its position shown in Fig. 2 by virtue of its distribution of weight, and that access to this ball is prevented by the baffle 28 and baffle cup 32. (Access to this ball is further prevented by supplementary means to be described.) The bottle is thus incapable of further use, and any attempt to pour out its contents is futile. This condition of the bottle provides evidence to the consumer that tampering has been attempted, and further proves to the offending person that it is useless to endeavor to tamper with bottles or other containers equipped with this device. The distance between the end of projection 23 and the bottom of the baffle 28 or baffle cup 32 may be very slightly greater than the diameter of the ball (by the order of a thousandth of an inch, for example), so that the ball may turn particularly freely as soon as it clears the projection. Such a clearance is unnecessary to permit turning of the ball, although it may be provided without interference with the effectiveness of the locking action above described.

The ball and cradle arrangement thus far described operates in substantially the same manner as the device disclosed in my prior patent above referred to. While I have described the operation of this portion of the mechanism with reference to an upright position of the bottle, it will be understood that it also is effective for other positions of the bottle, as described in my prior patent. When the bottle is turned upside down or with the neck end pointing downwardly at an angle, the ball 20 is floated beyond the projection 24 upon any attempt to fill the bottle, and due to its unbalanced condition, turns around in the same manner as has been described with reference to the action of the ball 19 when the bottle is upright during the refilling attempt.

In accordance with my present invention, the sleeve 12 and baffle 28 are retained against unauthorized removal from the neck of the bottle by means of the retainer 13 which also serves as a pouring element and as a mounting for the closure 14. This retainer element is provided with an attaching skirt 33 which is interiorly threaded as at 34 for engagement with complementary threads 35 formed on the outside of the neck of the bottle A near its end. In the embodiment illustrated, the retainer 13 tapers inwardly toward its upper end and terminates in

a substantially cylindrical pouring lip 36 which preferably is provided with an inwardly extending flange 37 for a purpose to be described.

The interior wall portion 38 of the retainer cooperates with a roller 40 and a cam surface 41 formed in the edge of the flange 15 of the sleeve 12 to prevent unauthorized removal of the retainer, or to fracture the retainer upon application of sufficient force. Suitable means 10 are provided for preventing the sleeve 12 from turning relative to the bottle neck as, for example, by providing it with longitudinally extending ribs 42 arranged for engagement with the corresponding grooves in the bottle neck. 15 The cam surface 41 may be formed by simply providing a notch in the flange 15 of the sleeve, the end 43 of this notch extending substantially in a radial direction as shown clearly in Fig. 5. Since, in the embodiment illustrated, the 20 threaded engagement between the retainer and the bottle neck is right-handed, the retainer will be turned in a clockwise direction, as viewed in Fig. 5, during its application to the bottle. This clockwise motion is performed freely because the 25 roller 40 rests against the upright wall 43 at the end notch in the flange 15 of the sleeve and exerts no camming action. When, however, it is attempted to remove the retainer, the roller 40 is carried part way up the inclined cam surface 30 41 of the notch so that it is wedged tightly between that surface and the inside of the wall 38 of the retainer. It will be clear that the greater the force exerted in an attempt to remove the retainer, the tighter will be the lock between the 35 retainer and the sleeve by reason of the aforesaid camming or wedging action. When the force applied is very substantial, the retainer 13 will be ruptured under this wedging action which, of course, provides evidence to the consumer that tampering has been tried. The 40 retainer 13 preferably is made of a molded plastic composition with the desired fracturing characteristics.

Another feature of my invention resides in the provision of means cooperating with the aforesaid container element and tamper-proof locking means for preventing accidental operation of said locking means. With the construction thus far described, it is possible, under certain conditions, 45 for the ball 19 to be joggled into the position shown in Fig. 2 even in the absence of an attempt to refill the bottle, or for the ball 20 to be lifted from the projection 24 so as to lock the container against pouring of its contents. 50 For example, with the closure 14 in place, the bottle might be laid upon its side during shipment in a train or other vehicle, and the jouncing of such vehicle could quite easily result in accidental operation of the tamper-proof locking means. 55 In order to eliminate such a possibility, I have provided auxiliary means for disabling the locking means so that when the closure is in place, it is impossible for the means to actuate. In my preferred embodiment, the disabling means 60 consists essentially of a reciprocable plunger member 44 arranged between the closure 14 and the ball 19 in such a way that when the closure 14 is in place, the parts will be held in the position shown in Fig. 1 so that the balls 19 and 20 65 cannot be freed from the projections 23 and 24 of the hub 21. In this position, the ball 20 closes the opening 17 in the lower wall 16 of the well. 70

In the embodiment illustrated, the plunger 44 is slidably arranged in an aperture 45 in the baffle 28. At its upper end, the plunger is con-

nected by arms or spokes 46 to a sleeve 47 slidably arranged within the cylindrical portion 36 of the retainer 13. A coil spring 48 surrounding the plunger 44 bears at one end against the top of the baffle 28 and at its other end against the under side of the plunger top, exerting a force which lifts the plunger into the position shown in Fig. 2 when the closure 14 is removed. The flange 37 at the top of the retainer or pouring element serves as a limit stop for the sleeve 47 of the plunger. While, as previously described, the plunger 44 when in the position shown in Fig. 1 with the closure in place, effectively prevents accidental operation of the locking means, it will be observed that when the closure is removed and the plunger is lifted by the spring 48 into the position shown in Fig. 2, the tamper-proof locking means becomes effective for its intended purpose.

Inasmuch as the plunger 44 provides means for disabling the tamper-proof locking means, it is to be supposed that anyone seeking to tamper with the container might be led to attempt to use the plunger 44 as a means for disabling the tamper-proof locking means even when the closure 14 is removed, as for example, by pushing down on the plunger with a suitable instrument. Such an attempt, however, will be futile with the arrangement I have devised because the sleeve 47 is arranged to seal the pouring opening at such times as the disabling means is effective by reason of interception of the ball radius by the plunger 44. For this purpose, the sleeve 47 is arranged to cooperate with an upwardly and outwardly extending annular flange 49 formed on the baffle 28. Fig. 3 shows the plunger 44 partially depressed, as it might be during an attempt to disable the tamper-proof locking means. The plunger has reached the lowest or innermost position which it can occupy and still permit operation of the locking means. That is to say, if the plunger is pushed in any further, the locking means can be disabled, or prevented from operating. However, in the positions shown in Figs. 2 and 3, or in any intermediate position, the operation of the locking means is not affected by the plunger. It will be understood, therefore, that in order to depress the locking means, it is necessary to depress the plunger to an extent greater than indicated in Fig. 3, and in such a position, the sleeve 47, which is attached to the plunger, completely closes the opening between the flange 49 and the cylindrical portion 36 of the pouring element. Thus, a seal is provided for any position of the plunger that could be effective in disabling the locking means and there is no space through which a siphon tube or other instrument could be inserted.

From the foregoing description, it will be seen that I have provided apparatus adapted to be inserted into a portion of a liquid container, such as the neck thereof, for protecting the contents of the container, said apparatus being responsive to introduction of liquid into said portion for movement into a position permanently locking the container against further use; that I have provided further, means for preventing accidental locking of the container against further use when the outer closure is in place; and that I have provided means for preventing the last-named means from being used as a device for disabling the locking means when the closure is removed. The last-named means closes the pouring opening in the retainer element when the means for preventing accidental actuation of the

locking means is manually operated. The retainer element serves as a pouring spout, receives the outer closure or cork, provides a guide and stop for the sleeve of the plunger (44), and prevents removal of any part of the assembly without fracturing the retainer itself.

The terms and expressions which I have employed are used as terms of description and not of limitation, and I have no intention, in the use of such terms and expressions, of excluding any equivalents of the features shown and described, or portions thereof, but recognize that various modifications are possible within the scope of the invention claimed.

I claim:

1. Apparatus adapted to be inserted into a portion of a liquid container for protecting the contents thereof, said apparatus comprising means responsive to the entrance of liquid into said portion from the exterior of the container for permanently locking said container against pouring of its contents, a closure member, and means cooperating with said closure and said locking means for preventing accidental locking of said container against pouring of its contents.

2. Apparatus adapted to be inserted into a portion of a liquid container for protecting the contents thereof, said apparatus comprising means responsive to the entrance of liquid into said portion from the exterior of the container for permanently locking said container against pouring of its contents, a closure member, and means cooperating with said closure and said locking means for engaging said locking means to prevent locking thereof when said closure is in place.

3. Apparatus adapted to be inserted into a portion of a liquid container for protecting the contents thereof, said apparatus comprising a member for closing a pouring opening for said contents and movable away from said opening in response to tilting of said container for pouring said contents, means responsive to the introduction of liquid into said container portion for permanently locking said member in a position wherein said opening is closed, a closure member, and means cooperating with said closure and said locking means for preventing response of the locking means to liquid entering said portion from within the container.

4. Apparatus adapted to be inserted into a portion of a liquid container for protecting the contents thereof, said apparatus comprising means including a normally unbalanced member responsive to introduction of liquid into said portion for movement into a position permanently locking said container against further use, a closure member, and means arranged for engagement by said closure member for holding the unbalanced member against movement into said locking position when said closure is in place.

5. A tamperproof attachment for a liquid container comprising a pouring element, a closure for the pouring element, refill preventing means, means in said pouring element for disabling said first-named means when said closure is in place, and auxiliary means for closing the pouring opening in said element when said disabling means is manually operated with said closure removed.

6. A tamperproof attachment for a liquid container comprising a pouring element, a closure for the pouring element, means for locking the container against removal of its contents upon

attempted refilling of the container, a baffle within the pouring element, a reciprocable member and means for holding said reciprocable member in position to prevent accidental actuation of said locking means, said holding means comprising a member arranged to close the space between the baffle and pouring element when said holding means are in holding position.

7. Apparatus adapted to be inserted into a portion of a liquid container for protecting the contents thereof, said apparatus comprising a member for closing a pouring opening for said contents, spacing means movably mounted in said portion and engaging said member, a second member engaging said spacing means, means limiting movement of said second member away from the spacing means, the first mentioned member being adapted to move into a position

wherein it is locked between said spacing means and said opening in response to introduction of liquid into said container portion when the container is in certain positions, and said second member being adapted to move into a position where it is locked between said limiting means and said spacing means to lock the first member in closing position in response to introduction of liquid into said container portion when said container is in other positions, an outer closure element, and a reciprocable element arranged for engagement with one of said members for preventing either of said members from moving into said locked positions when the outer closure element is in place and in engagement with said reciprocable element.

LYNDON G. STONEBRAKER.
